UNITED STATES PATENT OFFICE.

CHARLES W. WILSON, OF NEW YORK, N. Y.

UMBRELLA.

1,210,126.

Specification of Letters Patent. Patented Dec. 26, 1916.

Application filed December 9, 1915. Serial No. 65,882.

To all whom it may concern:

Be it known that I, CHARLES W. WILSON, a citizen of the United States, residing at New York, in the county and State of New York, have invented new and useful Improvements in Umbrellas, of which the following is a specification.

This invention relates to certain novel and useful improvements in an umbrella having a sight opening or openings therein for the purpose of enabling the user to have an unobstructed view in a desired direction, even though the umbrella be so tilted as to shield the head and face of the person against a driving storm, for instance, a position which with the ordinary umbrella would of course interfere with the vision.

In the present instance it is my purpose to provide an umbrella having one or more openings cut therein and covered with a celluloid or other transparent material thus forming windows through which a person may readily and clearly see in a desired direction when the umbrella is open. When the umbrella is closed, however, these windows will not only be concealed from ordinary observation, but will be so positioned as not to interfere with the usual wrapping or rolling of the umbrella cover about the stick.

It is also my purpose to provide an article of this class wherein the transparent sheets or panes for the openings are so secured to the cover of the umbrella that the latter will be rendered water-tight at the points of attachment of the panes and at the same time the latter may be readily and quickly applied to and removed from the cover when desired. Furthermore, I propose to provide an umbrella having a pair of spaced sight openings or windows in the cover thereof with the transparent panes of the windows arched or curved in opposite direction so that while the umbrella is open, the panes will lie substantially flat and will not interfere with the vision, yet when the umbrella is closed one pane will overlie or nest with the other pane so that the umbrella may be neatly rolled or folded.

With the above recited objects and others of a similar nature in view, my invention consists in the construction, combination and arrangement of parts set forth in and falling within the scope of the appended claims.

In the accompanying drawings, Figure 1 is a view of an umbrella having my invention applied thereto, the umbrella being

shown in its open position. Fig. 2 is an enlarged detail view of a portion of the umbrella cover broken away, and showing one manner of securing the transparent sheet or pane at the window opening in the cover, such view being also shown partly in section. Fig. 3 is a detail sectional view taken through a portion of one of the transparent panes and through the adjacent bindings which connect the pane with the cover. Fig. 4 is a horizontal sectional view taken through a section of the cover partially collapsed or folded and showing the opposing curvatures of the two transparent panes. Fig. 5 is a sectional view taken through a portion of the cover when the umbrella is substantially closed and illustrating how the two panes nest or lie one within the other.

Referring now to the accompanying drawings in detail and especially to Fig. 1 thereof, the letter A indicates an ordinary umbrella stick, while B is the usual fabric cover adapted to be held in its open position by suitable ribs C. This cover is of course divided into the usual panels or sections by ribs, one of said panels being designated by the letter D. In the present instance, this panel D has cut therein a pair of spaced openings 1 and 2 which lie substantially in horizontal alinement, or in parallelism when the umbrella is open as is clearly shown in Figs. 1 and 2. As will be seen by reference to Fig. 4, the opening 1 is covered or provided with preferably an approximately circular pane or transparent sheet 3 which is curved or bowed inwardly, while likewise the opening 2 is provided with preferably an approximately circular transparent sheet or pane 4 which is curved or bowed outwardly, or in an opposite direction to the transparent sheet or pane 3, the result being that when the umbrella cover is closed, as shown in Fig. 5, the two transparent panes will nest or lie one within the other and conform to the general contour of the closed umbrella cover. These panes may be fastened to the cover of the umbrella in any suitable way, an exceedingly simple manner of fastening the panes being shown in Figs. 4 and 5. In this instance, each transparent pane is fastened to the edge wall portion 5 surrounding each opening in the cover by means of the circular binding strip 6, preferably of fabric, and suitable stitches 7, each pane adjacent its periphery having a suitable number of small holes or perforations

105

110

therein through which the stitches 7 may pass. Each binding strip 6 is of course sewed or stitched to the adjacent portion of the cover by means of suitable threads 8.

5 The preferred manner of fastening each sheet or pane is shown in Figs. 2 and 3. Referring to Fig. 2, the circular wall portion 5 of the cover surrounding the opening is turned or folded inward as at 9, and to 10 this fold 9 is stitched the folded edge 10 of the binding strip 11, preferably fabric, the other edge of this strip 11 being also folded inward as at 12. A transparent pane, for instance the pane 3, is placed between this 15 binding strip 11 and the inner circular binding strip 13, also of fabric, the latter lying against the inner face of the adjacent section of the cover. This strip 13 is in the present instance folded centrally upon itself and 20 then refolded to form a four-ply binding as is clearly shown in Figs. 2 and 3. A circular row of stitching 14 passes through and unites the inner binding strip 13, the binding strip 11 and the cover of the umbrella as 25 clearly shown in Figs. 2 and 3. Likewise the folded or tucked-in edge 9 of the cover is united to the adjacent folded edge 10 of the strip 11 by stitching as shown at 15. The transparent pane, which is shown as 30 positioned in the pocket or circular groove formed by the inner binding strip 13 and the binding strip 11, is fastened or secured in place by tacking, that is by short stitches 16 passing through perforations 17 in the 35 transparent pane. By so fastening the transparent pane to the cover as shown in Figs. 2 and 3 I insure that the umbrella will be water-proof, that is to say will not leak at this point when in use.

40 From the above description taken in connection with the accompanying drawings the construction and manner of using the invention will be readily apparent. Owing to the flexible nature of the cover, it will be 45 seen that when the umbrella is open, the two windows in the panel D will be drawn apart or separated as shown in Fig. 1, under such conditions the transparent panes instead of being slightly bowed as shown in Figs. 4 50 and 5 will be stretched substantially flat as shown in Fig. 3. Thus windows will be provided through which the user may look in the desired direction, thereby enabling him to see clearly even though the umbrella 55 be tilted to shield the head and face. With the ordinary umbrella, when the article is so tilted, it is of course impossible for the person to see directly ahead, the line of

vision being obscure by the cover portion of the umbrella. Now, when my improved 60 umbrella is folded, owing to the peculiar curvature of the transparent panes, one of said panes will nest or lie within the other as shown in Fig. 5, the cover of the umbrella 65 partially folded or collapsed being shown in Fig. 4 and indicating to some extent the manner in which the panes are moved toward each other into nested position. When the umbrella is completely collapsed the curvature of the panes will conform to the 70 approximately cylindrical bundle made by the stick and the ribs, and the cover may be neatly and conveniently rolled without any interference whatsoever on the part of the windows and without injuring or 75 breaking the latter.

In the present instance I have shown the preferred form of my invention, wherein the umbrella is provided with a pair of spaced windows or openings in one of the 80 panels or sections of the cover, but I wish it to be understood that it is not limited to any particular number of windows. For instance, if desired, a relatively large single window may be employed.

While I have herein shown and described one particular embodiment of my invention, I wish it to be understood that I do not confine myself to all the precise details of construction herein set forth by way of illustration, as modification and variation may be made without departing from the spirit of the invention or exceeding the scope of the appended claims.

What I claim is—

1. An umbrella having a pair of spaced sight openings formed in the cover thereof and a pair of normally arched sheets of flexible transparent material covering said openings and adapted to nest one within the 100 other and conform to the roll of the cover when the umbrella is closed.

2. An umbrella having a pair of spaced sight openings therein and a normally arched transparent sheet or pane of flexible 105 material for covering each opening, said sheets or panes being adapted to nest one within the other and conform to the roll of the cover when the umbrella is closed.

In testimony whereof I have hereunto set 110 my hand in the presence of two subscribing witnesses.

CHARLES W. WILSON.
